LADY'S SHOE HEEL

Howard G. Crawford, 2129 Sierra Road,
Plymouth Meeting, Pa.

Filed May 14, 1962, Ser. No. 70,111

Term of patent 14 years

(Cl. D7—5)

Fig. 1

Fig. 2

Fig. 3

FIGURE 1 is a side elevational view of a lady's shoe heel, showing my new design;

FIGURE 2 is a rear elevational view thereof; and

FIGURE 3 is a top perspective view taken from the angle shown by the line 3—3 on FIGURE 1.

The top and the front of the heel are of conventional configuration.

I claim:

The ornamental design for a lady's shoe heel, as shown and described.
